UNITED STATES PATENT OFFICE.

JNO. BEATTIE, OF LIVERPOOL, ENGLAND.

MEANS FOR SUPPORTING THE PROPELLER-SHAFT AND RECEIVING THE RUDDER OF STERN-PROPELLERS.

Specification of Letters Patent No. 14,081, dated January 15, 1856.

To all whom it may concern:

Be it known that I, JOHN BEATTIE, of Liverpool, in the county of Lancaster, England, engineer, a subject of the Queen of 5 Great Britain, have invented or discovered certain new and useful Improvements in Constructing Vessels Propelled by Submerged Propellers; and I, the said JOHN BEATTIE, do hereby declare that the nature 10 of my said invention and the manner in which the same is to be performed is particularly described and ascertained in and by the following description thereof, reference being had to the drawings hereunto 15 annexed and to the letters and figures marked thereon.

My improvements consist in a peculiar construction of the after part of a ship or vessel which enables me to place the propeller beyond the rudder with perfect safety 20 by passing the shaft of the propeller directly through the rudder and through an inner and outer stern post, the shaft being supported by and resting upon the said 25 outer stern post.

In the accompanying drawing Figure 1 represents an elevation of the rudder and its appendages with the propelling shaft carried through the rudder.

30 A and B indicate the rudder formed in two parts which are connected together by being firmly affixed to the rudder post C C.

Through the middle of the rudder post an elongated hole is formed shown in the 35 transverse view of the central part of the

rudder post in Fig. 2 which hole is to allow the propelling shaft D to pass freely through whatever may be the angular position of the rudder. The stern post consists of a strong iron frame E E E affixed 40 vertically and forming one piece with the keel H at the stern of the vessel, hence the stern post embraces and carries the rudder A B which is hung upon hinges or centers, and is worked by the ordinary apparatus 45 attached to the top of the rudder post C.

The propelling shaft D D is put in motion in the ordinary manner by a steam engine within the vessel and has a bearing in the stern post beyond the rudder as shown 50 at Fig. 3. To the outer end of the propelling shaft the boss F carrying the vanes or paddles G G is to be keyed.

I would state that it is not new to have the rudder divided, nor is it new to place 55 the propeller beyond or astern of the rudder, and I make no claim thereto.

Having thus described the nature of my said invention and the manner of performing the same I would have it understood 60 that what I claim is—

The construction of an open wrought iron stern frame E E E forming part with the keel H of the vessel and receiving the rudder substantially as above described.

JOHN BEATTIE.
